DEVICE FOR THE PROMOTION OF CHIMNEY
INTAKE

Armin Burger, Wabern-Berne, Switzerland

Application May 31, 1945, Serial No. 596,962
In Switzerland December 5, 1944

2 Claims. (Cl. 98—78)

1

This invention relates to a device for the promotion of chimney intake.

The air-current of the chimney, as is well known, is affected detrimentally by the action of the wind on the chimney aperture and on the warmth of the air, so that chimneys have been provided with cowls which turn with the wind and prevent any down-draught. These metal cowls are attacked by the heating gases and are not reliable. Even the covering of the mouth of the chimney by means of sheets does not bring about the desired result.

The present invention relates to a cowl for chimneys of the kind comprising superposed hollow rectangular sections and curved passages for air formed between adjacent sections, said passages passing upwardly and inwardly towards the central vertical axis of the chimney and being of increasing cross-section towards said central axis. It is characterised in that the said passages are arranged vertically one above the other and in that the bounding lines of their curved surfaces lying respectively in vertical planes containing the central axis of the chimney, if continued, converge on one another and on the said central axis at a point above the chimney, whereby the air currents led to the interior of the cowl by the said passages are concentrated onto the central part thereof and better extraction of the gases from the chimney is obtained.

Preferably the uppermost passage is wider in cross section than the passages lower down and the interior cross-section of the uppermost part is larger than that of the chimney cross-section and of that of the parts situated beneath it.

A body of substantially lozenge-shaped cross-section can be provided in the central opening of the uppermost rectangular section of the cowl, the two upper surfaces of which body have a slightly concave curvature and lie substantially parallel to the lines of curvature of those passages situated at the corresponding side of the cowl.

In the drawing some embodiments of the invention are illustrated by way of example.

Fig. 1 shows a diagrammatic view of the upper portion of a chimney with the cowl device fitted to it.

Fig. 2 is a plan of Fig. 1.

In Fig. 3, is a vertical section of Fig. 1, showing an upward current of air.

Fig. 4 shows in perspective, the same embodiment as in Fig. 3, but when a gentle side wind enters from above.

2

Fig. 5 shows in perspective the same embodiment as in Figs. 3 or 4 but when a wind enters perpendicularly from above.

The drawings show the three uppermost courses 1 of bricks of a chimney upon which is placed a section 2, the interior of which is filled with filling material 4 such as cement, up to the upper edge 3 on which is the interior cross-section of the chimney. Above this lie two further similar body sections 5 and 6, which are kept at a distance from each other by means of props 7 at the four corners. Upon the body section 6 is fixed an upper body section 8 forming the top and whose interior cross-section at 9 is larger than the interior cross-section of the chimney itself, being conveniently so much larger as to correspond with the increase in volume of the flue-gas by the volume of air which enters through the passages 15, 16.

An essential characteristic of the present invention is, that the curved passages 15, 16, formed between two adjacent sections extend upwardly at an acute angle towards the axis of the chimney A—B and that they flare increasingly towards the interior of the chimney, that is towards the axis A—B, as can be seen from the drawing. The passages 15, 16, are therefore narrower in height on the outside in the neighbourhood of the props 7 than at the inner upper edges 3, 10 and 11 as well as being curved and convex towards the axis of the chimney A—B, as may be observed in particular from Fig. 2. The upper edges 3, 10, 11 are therefore not straight lines, but lines arched towards the axis of the chimney. Moreover, the cross-section of the upper passage 16, which is formed by the upper part 8 and the part 6 situated beneath it, is larger than the cross-section of the lower passage 15.

With rising winds, the air current, as can be seen from Fig. 3, blows upwards through the passages 15, 16, as indicated by the arrows, and imparts an additional draught to the flue-gases. If the wind strikes from the side, somewhat obliquely from above, against the cowl according to the present invention, it penetrates, as is illustrated in Fig. 4, into the passages 15, 16, is directed upwards and likewise imparts an additional upward speed to the smoke. But even with eddy currents striking perpendicularly upon the chimney no disturbance of the intake of the chimney, but an improvement in lift, is obtained, as is shown in Fig. 5. Here too, the wind currents, which is represented by arrows strike directly on to the interior cross-section of the upper rim 9,

hit the inserted body 12 and are diverted sideways into the uppermost passage 16. Since this uppermost passage 16 and the interior cross-section of the upper body 9 are larger than the adjacent passage 15 and the cross-section of the bodies 10 and 11, no back-pressure occurs, but, as shown by practical tests a lift enters the passage 16, so that the draught is not affected.

The same thing occurs when an eddy current occurs, as is shown in Fig. 5, so that in any event a suction of the flue-gases is attained. According to the present invention, the drawback that the chimney does not draw in warm weather because the specifically heavier column of flue-gases in the chimney has no lift against the lighter outside air, is also obviated. The warm outside air rises through the section passage like the upward current in Fig. 3 and creates a draught which is all the stronger the greater the difference in temperature between the outside air and the inside air. These facts have been confirmed by means of comprehensive practical experiments.

According to a particular embodiment of the invention, a streamlined body, e. g. a prism 12, is fixed on the rim 9 of the uppermost section 8 by means of a shoulder 14 having suitably spherically curved side surfaces 13. The prism 12 should conveniently be situated so that its upper edge points from south to north, if, as is most often the case, east or west winds prevail in the neighbourhood. Even the most piercing eddy wind is then so diverted, that it never blows into the fireplace, but always creates an additional draught which increases with the strength of the wind. Consequently this embodiment is particularly suited to firing installations which can only have a short chimney, as e. g., land or water vehicles, or in the case of buildings in the mountains, at the edge of a wood and so on, where rather strong eddy winds are frequently to be reckoned with.

In consequence of the increase in draught obtained at any state of the wind and weather by means of the arrangement according to the present invention, not only is a faultless action of the firing installation obtained, but also a saving in fuel, since the temperature of the flue-gas may, as a result of the creation of additional draught, be lower than is usually requisite for the creation of the necessary lift. The slight expenditure for the fixing of the new section arrangement is therefore outweighed, after a short time, by the saving of fuel.

Patent claim.

1. Cowl for chimneys, of the kind comprising

superposed hollow rectangular sections and curved passages for air formed between adjacent sections, said passages passing upwardly and inwardly towards the central vertical axis of the chimney and being of increasing cross-section towards said central axis, characterised in that the said passages are arranged vertically one above the other and in that the bounding lines of their curved surfaces lying respectively in vertical planes containing the central axis of the chimney, if continued, converge on one another and on the said central axis at a point above the chimney, whereby the air currents led to the interior of the cowl by the said passages are concentrated onto the central part thereof and better extraction of the gases from the chimney is obtained.

2. Cowl for chimneys, as claimed in claim 1, wherein the central opening of the uppermost rectangular section is larger than those of the remaining sections and has a transverse deflector of lozenge-shaped cross-section inserted therein, said deflector having two upper concave surfaces which lie along the lines of curvature of those passages situated at the corresponding side of the cowl, whereby the air currents led to the interior of the cowl by the said passages are concentrated onto the central part thereof and better extraction of the gases from the chimney is obtained.
